UNITED STATES PATENT OFFICE.

JOHN GEORGE O'BRIEN AND FRANK A. PICARD, OF SAGINAW, MICHIGAN.

RESERVE-SUPPLY SYSTEM FOR TANKS.

1,425,681.

Specification of Letters Patent. Patented Aug. 15, 1922.

Application filed November 2, 1921. Serial No. 512,222.

To all whom it may concern:

Be it known that we, JOHN GEORGE O'BRIEN and FRANK A. PICARD, citizens of the United States, both residing at Saginaw, 5 in the county of Saginaw and State of Michigan, have invented certain new and useful Improvements in Reserve-Supply Systems for Tanks; and we do hereby declare the following to be a full, clear, and exact description of the invention, such as will enable others skilled in the art to which it appertains to make and use the same.

This invention relates to fuel reserve supply systems for tanks such as are used with 15 internal combustion engines and the like.

Our invention is particularly adapted to that class of fuel reserve supply systems having means for checking the flow of liquid from the tank when the content of the tank 20 has been reduced to an amount corresponding to the desired reserve. The user is thereby warned that the tank must soon be refilled.

The object of our improvement is to provide a one-piece handle which will operate 25 not only to open and close the outlet valve of the tank, but will also engage the filling plug of the tank when the outlet valve is opened, thereby preventing the filling plug 30 from being removed and consequently preventing the tank from being refilled until the handle member has been disengaged from the filling plug. When so disengaged, the handle automatically operates the outlet 35 valve to close it, thereby insuring another reserve supply when the tank is refilled.

The broad aspects of our present improvement as above outlined are described and claimed in our Patent No. 1,409,310, granted 40 March 14, 1922, to which reference may be had.

The present invention relates more particularly to a valve-actuating handle that operates by being moved in a horizontal 45 plane, the handle being so constructed that it, in combination with a cylindrical curved top tank, will automatically lift the valve when the handle is moved horizontally to engage the filling cap and will permit the 50 valve to close when the handle is moved crosswise the tank.

A further object of our present improvement is to provide an improved construction of valve employing a vertically tubular 55 valve stem, the valve case being so arranged that it can be readily screwed into the tank

outlet in place of the usual sediment receptacle, the case also being provided with a threaded socket to receive the threaded end of the sediment receptacle, or an equivalent pipe line connection is used on tanks not equipped with a sediment receptacle, this arrangement enabling the valve to be quickly applied to an existing fuel tank without the necessity of providing a separate tank outlet for the sediment receptacle.

With these and certain other objects in view, which will appear later in the specification, our invention comprises the devices described and claimed and the equivalents 70 thereof.

In the drawings, Fig. 1 is a longitudinal section through one end of a cylindrical fuel tank, showing our device in place.

Fig. 2 is an enlarged transverse section, 75 broken away in part, the section taken on the line 2-2 of Fig. 1, the handle being positioned at right angles to its position as shown in Fig. 1.

Fig. 3 is a longitudinal section of the 80 valve casing, the valve stem broken away in part.

As is clearly shown in the drawings, the device consists in the tank 1 having the usual filling cap and it may have a sediment receptacle 3, or its equivalent, communicating 85 with the outlet pipe 4.

In applying our improvement to a fuel tank of this kind, we first remove the sediment receptacle 3 and insert in its place the 90 threaded valve casing 5, which projects up into the tank from the bottom. The threaded valve casing 5 is provided with a socket 6 at its lower end, and the sediment receptacle 3, or other outlet connecting device, is 95 screwed into this socket, thereby connecting the outlet pipe 4 with the interior of the tank through the valve casing 5.

Connected to the upper end of the tubular valve stem 7 is a vertically movable rod or 100 bar 8. The upper end of this rod projects through an opening 9, which may be formed in the top of the tank by means of a punch or any similar tool.

The upper end of rod 8 is provided with 105 a pin or other suitable projection 10, and upon the rod and under the pin 10 is received a bar 11, preferably bowed upwardly as shown in Fig. 2. One end of this bar, as 12, is adapted to take against the top 110 13 of the tank when the bar is lengthwise the tank, as shown in Fig. 1 and the other

end 14 of the bar is adapted to engage and rest upon the filling cap 2. The upwardly bowed intermediate part of bar 11 thus holds the vertically movable rod 8 in its lifted 5 position, holding the valve 15 open and permitting the tank to drain through an opening 16 formed in the side of the valve casing 5 and communicating with outlet pipe 4 by way of the annular space around valve 10 15.

When bar 11 is turned to a position cross-wise the tank and at right angles to the position shown in Fig. 1, that is, to the position shown in Fig. 2, the bowed bar 11 permits the vertically movable rod 8 to drop 15 and close the valve 15. Rod 8 is preferably forced downwardly by means of a helical spring 17, which also compensates for expansion or distortion of the tank and prevents rattling. 20

For convenience in assembling, we prefer in practice to make the rod 8 sufficiently long so that its upper end 19 can easily be pushed through the opening 9, projecting 25 upwardly above the tank top.

After the parts are assembled, the upper end 19, which has preferably been notched as at 18, may be broken off, as indicated by the dotted lines in Fig. 1. When the valve 30 15 is closed, liquid is prevented from escaping through the opening 16, but may escape through the tubular valve stem 7, entering the valve through an opening 20 at a height corresponding to the depth of liquid 35 in the tank when the reserve supply is reached, and escaping through the lower end 21 of the valve stem.

A compressible spring 17^a may be employed in addition to spring 17, spring 17^a 40 surrounding the tubular stem 7 and retained in the case 5 by means of a plug 17^b, the lower end of the spring bearing upon the upper face of valve 15 to normally hold the valve closed.

45 By the means above described, we have produced a simple, efficient and inexpensive device for providing a reserve fuel supply system, the device so arranged that by the moving of a single one-piece handle so that it rests upon the filling cap, the outlet valve will be raised to drain the tank, and by moving the handle away from the filling cap, the handle, in combination with the curved top

of the tank, acts as a cam to permit the valve to close and thereby prevent draining the 55 tank to a point lower than the level corresponding to the desired reserve fuel supply.

We have also provided a simple and inexpensive valve construction that is not likely 60 to get out of order and that combines the functions of a stand-pipe for purpose of storing the reserve supply with the functions of an ordinary vertical lift valve.

Having thus described our invention, what we claim and desire to secure by Letters Patent is:

1. In combination with a tank having an outlet and a filling cap, a vertically movable hollow valve controlling said outlet, the casing of said valve formed with a threaded 70 socket, a tubular valve stem, a compressible spring within said casing and surrounding said tubular stem, a rod connected to the upper end of said tubular stem and projecting through the top of said tank, a one-piece bowed handle secured to the end of said rod, one end of said handle adapted to engage the top of said tank, the other end of said handle removably engaging said filling cap, whereby to open said valve. 75

2. In combination with a tank having an outlet and a filling cap, a vertically movable hollow valve controlling said outlet, a valve stem, a compressible spring within said casing and surrounding said stem, a rod pivotally secured to said stem, the upper end of said rod projecting through the top of said tank, a compression spring on said rod, a one-piece bowed handle secured to the end of said rod, one end of said handle adapted to engage the top of said tank, the other end removably engaging said filling cap. 80 85

3. In combination with a tank having an outlet and a filling cap, a vertically movable valve control, a valve stem, a compressible spring surrounding said stem, a rod pivotally secured to said stem, the upper end of said rod projecting through the top of said tank, a compression spring on said rod, a handle secured to the end of said rod, 90 said handle adapted to operatively engage the top of said tank, the other end removably engaging said filling cap. 95 100

JOHN GEORGE O'BRIEN.
FRANK A. PICARD.
